UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

DESIGN FOR A TONE-ARM FOR TALKING-MACHINES.

56,316.

Specification for Design.

Patented Sept. 14, 1920.

Application filed October 4, 1918. Serial No. 256,907. Term of patent 14 years.

To all whom it may concern:

Be it known that I, JOSEPH WOLFF, a subject of His Majesty the King of Great Britain, residing in the borough of Brooklyn, county of Kings, city and State of New York, have invented a new, original, and ornamental Design for Tone-Arms for Talking-Machines, of which the following is a specification, reference being had to the accompanying drawings, forming a part thereof.

In the drawings,—

The figure is a side elevation of a tone-

arm, illustrating my new design, the dotted lines showing the reproducer in two different positions.

I claim:—

The ornamental design for a tone-arm for talking machines, substantially as shown.

This specification signed and witnessed this 24th day of September, 1918.

JOSEPH WOLFF.
